CLAIM

The ornamental design for a combined cigarette and lighter holder, beverage holder and tray for an automobile dash, as shown.

DESCRIPTION

FIG. 1 is a right front perspective view of a combined cigarette and light holder, beverage holder and tray for an automobile dash in a closed condition showing my new design;

FIG. 2 is a right front perspective view of a combined cigarette and lighter holder, beverage holder and tray for an automobile dash in open condition;

FIG. 3 is a right front perspective view as taken from FIG. 2 with the cigarette and lighter holder in place and holder in fully extended position;

FIG. 4 is a top plan view;

FIG. 5 is a front elevational view;

FIG. 6 is a right side elevational view, the left side being a mirror image thereof; and

FIG. 7 is a bottom plan view.

FIG. 1
